CLAIM

The ornamental design for a dual-light lighting fixture, as shown and described.

DESCRIPTION

FIG. 1 is a bottom view of a dual-light lighting fixture showing my new design, in an untilted, closed position;

FIG. 2 is a bottom perspective view thereof;

FIG. 3 is another perspective view thereof;

FIG. 4 is a plan view of the dual-light lighting fixture, with the light bulb receivers angled right;

FIG. 5 is a perspective view of the dual-light lighting fixture, with the light bulb receivers angled right;

FIG. 6 is a plan view of the dual-light lighting fixture with a cover in an open position, with the light bulb receivers angled right and down;

FIG. 7 is a plan view of the dual-light lighting fixture of FIG. 6, with the light bulb receivers angled right; and,

FIG. 8 is a perspective view of the dual-light lighting fixture with a cover in an open position, with the light bulb receivers in a center position and angled down.

The broken lines shown in the drawings are for the purpose of illustrating portions of the dual light lighting fixture and form no part of the claimed design.
